UNITED STATES PATENT OFFICE.

NATHAN E. LEWIS, OF PLAINFIELD, NEW JERSEY, AND DOUGLAS WARD WILLIAMS, OF NEW BRIGHTON, STATEN ISLAND, NEW YORK, ASSIGNEES TO THE BABCOCK & WILCOX COMPANY, OF BAYONNE, NEW JERSEY, A CORPORATION OF NEW JERSEY.

FURNACE.

Application filed September 29, 1921. Serial No. 504,230.

Our invention particularly relates to a novel form of gas-burning furnace and to the novel form of gas-burning furnace in combination with an oil-burning furnace.

5 Our invention will best be understood by reference to the accompanying drawings, in which Figure 1 is a longitudinal section through a boiler setting and the associated furnace and the steam boiler which is heated by the furnace; Fig. 2 is a horizontal section, the parts of which from left to right are taken on the planes of the lines A—A, B—B and C—C of Fig. 1, and Fig. 3 is a view, partially in transverse section and 15 partially in front elevation, of the arrangement shown in Figs. 1 and 2.

Like reference characters indicate like parts throughout the drawings.

Referring, now, to the drawings, 10 is 20 the front wall, 11 the rear wall, and 12 and 13 the side walls of the setting. A combustion chamber 14 is enclosed between the front wall 10 and a bridge wall 15. The steam boiler, in connection with which 25 we have illustrated our invention, is of the Stirling type and comprises a mud drum 17, preferably located at the rear of the bridge-wall 15, to which are connected a plurality of banks of tubes 18, 19 and 20. The 30 front wall of the setting is preferably supported by a plurality of I-beams 21, as indicated in Fig. 1, an opening being provided between the I-beams and the base 22.

Oil is supplied to the furnace through a 35 pipe 23 controlled by a valve 24, the pipe preferably passing from the front to the rear of the furnace beneath the floor. In the form of burner illustrated, steam is supplied to the oil atomizer by a pipe 25 in a known manner. 40 The rear ends of the oil and steam pipes 23 and 25 are provided with upwardly-directed extensions 26 and 27 which lead to an atomizing nozzle 28, of known form. The extension 26 and 27 and the nozzle 28 are preferably located in an elongated transverse chamber 29 in the bridge-wall 15, as indicated in Fig. 2, so that the extensions 26 and 27 can be moved horizontally beneath the floor into position in the chamber 29 and then 50 turned upwardly to proper position. The bridge-wall 15 is also preferably provided with a forwardly bevelled opening 30 in front of the oil burner, through which a fan-shaped oil spray may be directed into the furnace. A hood 31 of refractory material 55 is preferably located above the chamber 29. We have illustrated three separate oil burners of the same or similar construction, and a separate flue or passage 32 is preferably provided for each of the oil burners, 60 the flues being separated by walls 33 extending from the base to the floor of the furnace. The oil burner and its associated parts illustrated, is similar to that shown in a patent to Irish No. 1,364,502, which was issued on 65 or about January 4, 1921.

Gas is supplied to the furnace by a main 34, to which are connected branch pipes 35 and 36 provided with valves 37 and 38 for controlling the gas supply from the respective branches. The gas burner, which we have indicated generally at 39, is divided into front and rear sections 39^a and 39^b, which are supplied with fuel from the respective pipes 35 and 36, the sections 39^b 75 preferably being located at a lower level than the section 39^a. Dividing the gas burner in the bottom of the furnace into a plurality of sections which are located at different levels, and bringing the air supply for the respective sections through passages located beneath the section at the higher level, is an advantage as it makes possible the use of 80 passages of ample proportions to carry the air supply to the respective sections which would not otherwise be possible and, at the same time, makes possible the use of a lower 85 setting than would otherwise be the case, it being understood that the height of the setting is determined by the distance between 90 the gas burner and the boiler tubes. The gas burner illustrated is also divided into a plurality of sections arranged transversely of the furnace, the respective transverse sections being located above the passages 32, 95 each transverse section preferably being supplied with gas from three pairs of pipes 35, 36, as best indicated in Fig. 2. To each of the pipes 35, which extend only beneath the front section 39^a of the burner, are connected 100 short laterally extending pipes 40, preferably extending from opposite sides of each pipe, as indicated in Fig. 2, each of the pipes being provided on the upper side with an opening 41. A hollow cylindrical tile 42 is 105 seated on the end of each of the pipes 40 and communicates therewith through the opening 41 and constitutes an individual gas

burner, the tiles passing through the floor of the furnace, which floor will be directly described. In a similar manner, the pipe 36 is provided, beneath the rear section 39^b of the burner, with laterally extending pipes 40, on which tiles 42 are similarly seated.

The floor of the furnace is preferably supported on rods or pipes 43, which are, in turn, supported on the walls 33, as best shown in Fig. 3. On the pipes 43 are laid refractory bricks or tiles 44 between the hollow tiles 42 and extending transversely of the furnace. These bricks are preferably laid flush with the upper ends of the tiles 42. Other bricks 45 are also laid between the tiles 42 and at right-angles to the bricks 44, the bricks 45 preferably being laid up above the upper ends of the tiles 42, as indicated in Fig. 3. The spaces 46 between the hollow tiles 42 and the bricks 44 and 45 are preferably packed with some refractory material, such as fire-clay and powdered asbestos, as at 47, to prevent air leaking through the floor and to protect the supporting ironwork underneath. Flat tiles or bricks 48 are preferably laid above the tiles 42 across the upper layers of bricks 45, which form a checkerwork therewith and constitute targets against which the gas flames from the burners impinge. It will thus be seen that the tiles 42 project through the floor of the furnace, the flame from the tiles passing upwardly between the bricks 45 and thence between the overlying bricks 48. A separate wind-box 49 is provided for each of the transverse sections beneath the front section 39^a of the gas burner, three such front wind-boxes, in the form illustrated, thus being provided. The tiles 42 of the front section 39^a project into the wind-boxes 49, as indicated in Fig. 1. Each wind-box 49 leads to the front of the furnace and the supply of air thereto is controlled by a door 51, hinged as at 52, to swing upwardly. Similarly, a wind-box 53 is provided for each of the rear sections 39^b of the gas burner, each of which is provided with a passage 54 leading to the forward end of the furnace, the air to each of these wind-boxes being controlled by a door 55, hinged as at 56, to swing downwardly.

The front wall 10 is preferably provided with a plurality of access and ignition openings 57, one for each of the transverse sections of the gas burner, each opening being provided at the front with a door 58 and preferably being partially walled up at the rear, as at 59. By removing the wall 59, more complete access may be had to the interior of the furnace. The front wall is also provided with peep-holes 60 closed by suitable doors 61, and the side walls are also preferably provided with peep-holes, as indicated at 62.

In accordance with our invention, the

front and rear sections of the gas burner, for which the gas and air supplies are separately controlled, may be separately operated. This is desirable under some circumstances where it is necessary to operate only one of the burners, particularly the rear burner. Furthermore, dividing the gas burner into sections and separately controlling the same, makes possible the operation, when desired, of one of the sections of the gas burner in conjunction with the oil burner. When it is desired to operate the oil burner, the operation of the gas burners is discontinued and the gas supply accordingly cut off. In accordance with our invention, however, the air supply for the rear section of the gas burner is utilized in the operation of the oil burner. The door or doors 55 are then opened, thereby admitting air to the wind-boxes 53, the air passing through the tiles 42 of the rear section 39^b of the gas burner beneath the oil spray, which is projected forwardly into the furnace by the oil atomizer.

In case it is desired to admit air at the rear of the furnace only to the fan-shaped oil sprays, those gas burners at the rear corners of each of the transverse sections of the gas burners located outside of the lines *a*—*b*, and indicated at 42^a, may be omitted.

What we claim and desire to secure by Letters Patent of the United States is:

1. In a furnace, a gas burner located in the bottom thereof and comprising a plurality of sections located at different levels, and independent air ducts located beneath the section at the higher level for conveying air to the respective sections.

2. In a furnace, a gas burner located in the bottom thereof and comprising a plurality of sections located at different levels from the front to the rear of the furnace, and independent air ducts located beneath the front section for conveying air to the respective sections.

3. In a furnace, a gas burner located in the bottom thereof and comprising a plurality of sections from the front to the rear of the furnace, the front section being located at a higher level than the rear section and independent air ducts located beneath the front section for conveying air from the front of the furnace to the respective sections.

4. In a combined oil and gas burning furnace, an oil burner located at the rear of the furnace and constructed and arranged to project oil in the form of a spray into the furnace, a gas burner located in the bottom of the furnace and divided into a plurality of sections from the front to the rear of the furnace, independent air ducts located beneath said gas burner, each duct being arranged to supply air to one section of the gas burner only, and independent means to

control the air supply to each of said ducts, the air duct leading to the section adjacent the oil burner being arranged to supply air to the oil burner.

5. In a combined oil and gas burning furnace, an oil burner located at the rear of the furnace and constructed and arranged to project oil in the form of a spray into the furnace, a gas burner located in the bottom 10 of the furnace and divided into a plurality of sections from the front to the rear of the furnace, with the sections from the front to the rear at progressively lower levels, independent air ducts located beneath said gas burner, each duct being arranged to supply air to one section of the gas burner only, independent means to control the air supply to each of said ducts, and the air duct leading to the section adjacent the oil burner being 15 arranged to supply air to the oil burner.

6. In a combined oil and gas burning furnace, an oil burner located at the rear of the furnace and constructed and arranged to project oil in the form of a spray into the 20 furnace, a gas burner having a plurality of 25

gas burner tubes located in the bottom of the furnace, means to supply combustion air to said gas burner and to said oil burner, and means to shut off the supply of air to a part only of the gas burner tubes while 30 air is being supplied to said oil burner.

7. A combined oil and gas-burning furnace comprising a floor, means for projecting an oil spray into the furnace comprising a pipe extending beneath the furnace floor 35 from the front to the rear of the furnace, and a gas burner divided into a plurality of sections from the front to the rear of the furnace and comprising hollow tiles projecting through the floor, independent 40 means for supplying air to the respective sections of said gas burner, and independent means for controlling the gas and air supplies to the rear section of said gas burner whereby the air supply to the rear gas 45 burner section may be utilized in the operation of the oil burner.
